UNITED STATES PATENT OFFICE

2,553,393

FURNACE WALL STRUCTURE

Herman W. Weber, Richmond Heights, Mo., assignor to Laclede-Christy Company, St. Louis, Mo., a corporation of Missouri

Application September 12, 1945, Serial No. 615,868

13 Claims. (Cl. 72—101)

1

The present invention relates to a wall support, and more particularly for a tile-supporting construction by which tiles of a refractory or the like nature may be supported on a wall framework.

It is an object of this invention to provide a tile support construction wherein there are brackets spaced at intervals and runners removably mounted thereon, with locking means to prevent accidental removal of the runners from the brackets. More particularly, it is an object to provide against such removal of the brackets under the influence of expansion and contraction forces acting upon the wall.

It is a further object to provide such locking means that may be readily operated when the assembly is set up, with a minimum of difficulty and with a minimum of parts, yet with assurance that the wall will be properly constructed regardless of the quality of workmanship.

A specific object is to provide a runner and runner supporting bracket that have rigid interlocking elements engaged when the parts are in operating position, so that the wall must be constructed in proper manner, and so that no parts can be omitted by accident or design.

In the drawings:

Fig. 1 is a vertical section of a wall employing the present construction;

Fig. 2 is a horizontal section taken on the line 2—2 at the upper part of Fig. 1;

Fig. 3 is a horizontal section taken on the line 3—3 at the upper part of Fig. 1;

Fig. 4 is a vertical section through one of the hangers or brackets, taken on the line 4—4 at the top of Fig. 1;

Fig. 5 is a front elevation of one of the runners;

Fig. 6 is a rear elevation thereof;

Fig. 7 is a side elevation of a short runner;

Fig. 8 is a rear elevation of one of the brackets;

Fig. 9 is a side elevation of the bracket;

Fig. 10 is a front elevation of the bracket; and

Fig. 11 is a side elevation of a runner supported intermediate its ends upon a single bracket.

This apparatus is designed to be used on a wall framework of any suitable kind. There is here shown a steel framework consisting of vertical beams 20 with transverse horizontal beams 21 and 22 secured thereto at spaced heights. It will be understood that the horizontal beams and vertical beams are in such number as to provide a framework over the entire wall. This framework may be vertical or horizontal, or may be arched, or disposed in any desired position.

2

In other words, the wall may be a side wall, a ceiling, a floor, or some angular or arched wall.

At suitable points in the framework, hangers or brackets are provided. They are horizontally spaced the distance between centers of the tiles, as shown in Fig. 2, and are vertically spaced the distance between the horizontal beams. In the present illustration, the hangers 24 and 25, bolted to the cross beam 21, typify the columnar spacing of the hangers, and the hanger 26, similarly bolted to the cross beam 22, illustrates the spacing within the columns. These hangers are shown in greater detail in Figs. 8—10. They are identical in principle of construction. Each includes a back plate 28, notched at 29 and 30 for receiving the attaching bolts 31 by which the hanger is secured to the beams. The notches provide for some lateral adjustment to accommodate irregularities of mounting.

20 Projecting forwardly from the back plate 28 is a web 33. This web is of greater vertical extent at its outer edge than at the back plate 28, and may be reenforced with ribs. It has at its forward edge an operating face 34 from which 25 project a pair of spaced hooks 35 and 36 and a pair of lugs 37 and 38. It will be seen that the hooks 35 and 36 are spaced apart approximately the same distance as are the two lugs 37 and 38. Between the lowermost parts of the hooks 35 and 36 is a locking dog 39. This slopes downwardly and outwardly, as shown particularly in Fig. 9, and has a transverse bottom ledge 40.

30 Tile holding runners are adapted to be hung in the hangers. Three such runners are shown in Fig. 1 at 42, 43 and 44, although, as will appear, the particular arrangement of Fig. 1 is not the only combination of parts. Similar runners will be connected with the other bracket series, such as that of bracket 24.

35 These runners are shown more in detail in Figs. 5 and 6. A somewhat shorter one is shown at 45 in Fig. 7.

40 Each runner is in the general form of a beam, having a web 47. The back edge of the web 47 receives a plurality of supporting pins 48 spaced therealong. These pins project outwardly from the opposite sides of the web, so as to be disposed transversely thereof. They are adapted to engage in the two hooks 35 and 36 of the hanger brackets while the web 47 is disposed between the two hooks. The back edge of the web 47 is also provided with a series of notches 49 that preferably slope inwardly and downwardly, as shown in Fig. 1 and Fig. 7 to provide a transverse ledge 50. These notches are so located

along the web 47 that one will receive the locking dog 39 of a bracket when any pair of the pins 48 is engaged in the hooks 35 and 36 of that bracket.

The webs 47 may be provided with a transverse reinforcing rib 51. From the front of this reenforcing portion, a plurality of tile holding elements, generally indicated at 53, project. Each comprises a spacer 54 extending outwardly in the plane of the web 47 and bearing a transverse holding plate 55 at its outer end. Thus, the tile holding elements are T-shaped in cross section. They are adapted to receive the T-slots in the tiles, as will appear.

The lowermost tile holding element on each of the runners is preferably provided with a bottom shelf 57 to give vertical support to the several tiles mounted upon the particular runner. When the lowermost set of pins 48 is engaged in the hooks 35 and 36, the bottom of the runner extends down approximately as far as the lugs 37 and 38. The bottom of the web 47 is cut away to provide a recess 58. The top of each runner is shaped at 59 to fit between the lugs 37 and 38, and in the recess 58 of the next runner, thereby to be secured against displacement.

Construction of the wall

The framework, consisting of the several beams 20, 21, 22, etc., is ordinarily of a permanent construction. The description thus far and to follow treats a vertical wall section, although it will be understood that this not a limitation.

It will be assumed that the hanger 26 is the start of the construction. This hanger will be bolted onto its cross beam 22 in proper alignment. Thereupon, the runner 43 will have its lowermost pins 48 disposed between the two hooks 35 and 36 of this hanger 26. In this operation, the depending part of the web 47 below the bottom locking notch 49 will slide downwardly over the locking lug 39 of the hanger. This will require a rocking movement of the upper end of the runner 43 from a position counterclockwise of that shown, to the position illustrated wherein the notch 49 is engaged over the lug, so that the two horizontal ledges 40 and 50 are brought together to prevent vertical movement of the runner when it is in the vertical position shown.

Thereafter the next upper hanger 25 can be installed. It will be applied to the beam 21 in a manner to slip its lower lugs 37 and 38 over the upper end 59 of the runner 43. Then it will be seen that it prevents backward or lateral movement of the top of the runner that would disengage it from the two lugs. Further clockwise pivoting of the bottom of the runner may be restricted by the engagement of the back face of the web 47 at the bottom against the operating base of the lower hanger 26.

The next higher runner 42 may then be secured to the hanger 25 in a similar manner. It disposes its lower recess around the top 59 of the runner 43, and thereby prevents clockwise rocking of the top end of the runner 43. Thus this runner is completely secured in position, and neither of its ends may become disengaged.

The several tiles may be installed on the runners in the manner known in the art, as illustrated by the applicant's copending application, Serial No. 603,201, filed July 4, 1945. Suffice it herein to say that the bottom tile 60 is inserted over the lowermost tile receiving element 54. All of the tiles have T-shaped slots to en-

gage over the T-shaped tile holding elements. The various tile holding elements are vertically spaced sufficiently far to permit the insertion of tiles between them. The bottom tile 60 is cut away to fit over the shelf 57. The tiles have tongue and groove interlocks, both on their sides and on their tops and bottoms. The lowermost tile 60 also preferably has a ledge interlock with the top tile of the lower course. The higher tiles, 61, 62, etc., are laid over the bottom one. The several tiles are united by cement.

The top tile 63 of this course cannot engage over a tile holding element and must be cemented into place, against adjacent tiles, and particularly the tile 70 of the course above.

Where the walls are in refractory furnaces and the like, any qualities of expansion become a problem. Heretofore, there has been a tendency for the forces of expansion to disconnect the runners from the hangers and thereby to permit the walls to come apart. The interlock members 39 and 49 between the brackets and the runners here prevent disconnection of the pins 48 from the hooks 35 and 36. Also, the upper ends of the runners are interlocked by the lugs 37 and 38 and their interfit with the depending ends of the next higher runners. The top part 59 of each runner may move vertically to accommodate expansion and contraction. This is permitted by the fact that the projection 59 does not extend to the top of the recess 48 under normal temperature conditions, but rather occupies a medial position therein sufficient to permit some relative vertical movement by expansion or contraction.

It will be seen that the brackets and runners are installed with a minimum number of parts. It is impossible to build the wall without constructing it properly with the several locking means and attaching means properly engaged. This overcomes oversight of workmanship that otherwise might cause a wall to come apart after it is completed. The several parts may be made of simple castings by the present construction, thus reducing the expense. As already noted, in the copending application, the provision of hangers that are separate from the runners permits modification of the spacing between the tiles and the steel framework by the simple substitution of different hangers, without changing the runners which may be standard all the way through. The runner of Fig. 7, however, illustrates a type of runner for fill-in purposes where the spacing between hangers is offsize.

It is not necessary that the wall be constructed precisely as shown in Fig. 1. The provision of an entire series of pins 48 permits a runner to be engaged intermediate its ends with a particular hanger. It may be seen from Fig. 11 that the engagement of a runner midway of its ends with a particular hanger provides a secure arrangement. In Fig. 11 a runner is shown supported on a bracket intermediate the ends of the former. A selected pair of intermediate pins 48 rests in the spaced hooks 35 and 36 of the bracket 25 and a portion of the web 47 of the runner extends between the spaced lugs 37 and 38.

It will equally be understood how the construction would be made for horizontal or angular or curved walls.

What is claimed is:

1. In a wall construction, a plurality of spaced hangers having hook means and spaced lugs spaced from the hook means, a plurality of tile holding runners, having tile engaging means at

the forward side thereof, having hook engaging means adjacent one end, and having a recess at said end, said hook engaging means on each of the runners being engaged with the hook means on a hanger, the other end of each runner being engaged between the spaced lugs of another hanger, and within the recess of an adjacent runner.

2. In a wall construction, a plurality of spaced hangers having hook means and spaced lugs spaced from the hook means, a plurality of tile holding runners, having tile engaging means at the forward side thereof, having hook engaging means adjacent one end, and having a recess at said end, said hook engaging means on each of the runners being engaged with the hook means on a hanger, the other end of each runner being engaged between the spaced lugs of another hanger, and within the recess of an adjacent runner, and locking means comprising interfitting portions of said hangers and runners preventing vertical movement of the runner and disengagement of its hook engaging means.

3. In a wall construction, a plurality of spaced hangers having hook means and spaced lugs spaced from the hook means, a plurality of tile holding runners, having tile engaging means at the forward side thereof, having hook engaging means adjacent one end, and having a recess at said end, said hook engaging means on each of the runners being engaged with the hook means on a hanger, the other end of each runner being engaged between the spaced lugs of another hanger, and within the recess of an adjacent runner, said end being disposed to occupy, at normal temperatures, only part of the recess, whereby expansion of the runner may be accommodated.

4. A tile supporting runner adapted to be hung on a support having hook means, the runner having tile supporting elements on the front side thereof, a plurality of pin means equally spaced along the runner for engagement in the hook means of the support, the runner extending below the pin means and being cut away on its back side to provide a recess extending inwardly from the end, the top of the runner being shaped in a manner complementary to the recess, and a plurality of locking elements equally spaced along the runner near each pin means.

5. A tile supporting runner for wall construction comprising a web, a tile supporting element and tile retaining elements extending forwardly from said web, a plurality of opposed pairs of spaced runner supporting pins extending laterally from the web along the rear edge thereof, and a locking notch formed in the rear edge of the web below each pair of pins.

6. A tile supporting runner for wall construction comprising a web, a tile supporting element and tile retaining elements extending forwardly from said web, a plurality of opposed pairs of spaced runner supporting pins extending laterally from the web along the rear edge thereof, and a locking notch formed in the rear edge of the web below each pair of pins, said web including a portion extending above the tile retaining elements, said web being cut away at its lower end to a point about the tile supporting element.

7. In a wall construction, in combination, a hanger member, a runner member removably supported on said hanger member in position to support tiles, interfitting attaching means between said members removably supporting said runner member on said hanger member, said interfitting attaching means including interen-

gaging hanger member and runner member portions, and locking means preventing relative displacement movement between said hanger and runner members, said locking means including 5 interengaging hanger member and runner member portions spaced from said first-mentioned hanger member and runner member portions.

8. In a wall construction, in combination, a plurality of hanger members, a plurality of runner members removably supported on said hanger members in positions to support tiles, each runner member being supported on an adjacent hanger member, interfitting attaching means between each runner member and the adjacent supporting hanger member removably supporting said runner member on the adjacent hanger member, said interfitting attaching means including interengaging hanger member and runner member portions, and locking means preventing 15 relative displacement movement between each runner member and its adjacent supporting hanger member, said locking means including interengaging hanger member and runner member portions spaced from said first-mentioned hanger member and runner member portions.

9. In a wall construction, a hanger member, a tile supporting member mounted on the hanger member, interfitting attaching means on said members separable in one direction fitted together 20 in removable supporting relation of said tile supporting member on said hanger member, said tile supporting member being swingable about said interfitting attaching means for removal from said hanger member, and interengaging locking elements on said members, said interengaging locking elements being spaced from said interfitting attaching means.

10. In a wall construction, a hanger member, a tile supporting member mounted on the hanger member, interfitting attaching means on said members separable in one direction fitted together in removable supporting relation of said tile supporting member on said hanger member, said interfitting attaching means comprising hook means on one member and pin means on the other member, said tile supporting member being swingable about said interfitting attaching means for removal from said hanger member, and interengaging locking elements on said members, said 25 interengaging locking elements being spaced from said interfitting attaching means.

11. In a wall construction, a hanger member, a tile supporting member mounted on the hanger member, interfitting attaching means on said members separable in one direction fitted together 30 in removable supporting relation of said tile supporting member on said hanger member, said interfitting attaching means comprising hook means on one member and pin means on the other member, said tile supporting member being swingable about said interfitting attaching means for removal from said hanger member, and interengaging locking elements on said members, said 35 interengaging locking elements being spaced from said interfitting attaching means.

12. In a wall construction, in combination, a hanger member including opposed hook portions and a pair of opposed lugs spaced from said hook portions, and an elongated runner member removably supported on said hanger member, said elongated runner member including a web and a plurality of equi-spaced opposed pairs of pins along one edge of said web and tile supporting 40

and retaining means along the opposite edge of said web, a selected pair of said pins supportingly engaging said hook portions, said web extending between said lugs.

13. In a wall construction, in combination, a hanger member including opposed hook portions and a pair of opposed lugs spaced from said hook portions, and an elongated runner member removably supported on said hanger member, said elongated runner member including a web and a plurality of equi-spaced opposed pairs of pins along one edge of said web and tile supporting and retaining means along the opposite edge of said web, a selected pair of said pins supportingly engaging said hook portions, said web extending between said lugs, said hanger member also including a locking lug and said runner member including a locking notch adjacent each pair of pins, said locking notch adjacent said selected pair of pins being disposed in locking engagement with said locking lug.
